SEAL FOR FLOATING TANK ROOFS

John H. Wiggins, Tulsa, Okla.

Application March 15, 1930, Serial No. 436,217

24 Claims. (Cl. 220—26)

This invention relates to liquid storage tanks of the kind that are provided with a roof or top which floats upon the liquid in the tank, and particularly floating tank roofs of the type in which 5 the means used to seal the space between the peripheral edge of the roof and the side wall of the tank comprises segmental shoe members arranged vertically in parallel or substantially parallel relation with the side wall of the tank and 10 supported from the roof in such a way that they are capable of moving radially with respect to the roof, and a flexible or pliable medium, usually gas-tight fabric, that is combined with the shoe members and with the upwardly-projecting rim 15 at the peripheral edge of the roof in such a way as to produce what is commonly referred to as a "seal".

One object of my present invention is to provide a floating roof seal whose component 20 parts are of such construction and arrangement that the seal can be installed or removed in much less time than seals of conventional design, and the various operations required in the assembling, disassembling, mounting or dismantling 25 of the parts of the seal, can be performed by workmen located on the top side of the roof.

Another object is to provide a seal of the kind mentioned, which is of such design that it is practicable to make the parts of same of lighter 30 gage metal than is used in conventional floating roof seals, thereby reducing the weight and cost of the seal.

Another object is to provide a seal whose segmental shoe members are constructed from relatively thin metal plates that will flex readily and conform to the approximate curvature of the side wall of the tank and to the vertical seams in same, even though only a relatively slight outward force or pressure is exerted on the shoe 40 members.

Another object is to provide a seal for a floating tank roof whose parts can be assembled without the necessity of forming numerous matched or aligned holes in the metallic parts and fabric 45 parts of the structure, as is necessary with floating tank roof seals of conventional design.

Another object is to provide a seal which is of such construction that a coating of paint or other protecting material on the shoe members will 50 not be liable to be rubbed off by relative movement between the shoe members and side wall of the tank.

And still another object is to provide a seal for floating tank roofs, which is of such design that 55 it is practicable to make the shoe members ap-

proximately twice as long as the shoe members used in seals of conventional design, thus reducing the number of vertically-disposed pieces of fabric attached to the adjacent ends of the shoe members. Other objects and desirable features 60 of my invention will be hereinafter pointed out.

Figure 1 of the drawings is a vertical sectional view of my improved seal for floating tank roofs, taken longitudinally through one of the carriers and illustrating the means that is employed to 65 sustain said carrier, the means used to combine said carrier with the shoe member with which it co-operates, and the means used to attach the horizontally-disposed fabric to the shoe member and to the rim of the roof.

Figure 2 is a vertical sectional view of one 70 of the shoe members, illustrating how the guides are attached to same.

Figure 3 is a detail view, illustrating the clips or devices that are attached to the carriers at 75 the points where the hangers are pivoted to the carriers, so as to clamp the upper edge portion of the shoe member against the carrier.

Figure 4 is a horizontal sectional view, illustrating the construction of the means that is used 80 to join the vertically-disposed pieces of fabric to the adjacent ends of the shoe members.

Figure 5 is a side elevational view of the parts shown in Figure 4, looking outwardly towards 85 the side wall of the tank.

Figure 6 is a fragmentary side elevational view of the seal, looking outwardly from the center of the roof, showing the rim at the peripheral edge of the roof and the co-acting parts or members of the seal located beyond or outside of said 90 rims; and

Figures 7 and 8 are detail views, illustrating other ways of securing the fabric member F.

In the drawings which illustrate the preferred form of my invention, A designates the side wall 95 of a liquid storage tank, B designates a floating roof or top that rests upon and is sustained by the liquid x in the tank, as shown in Figure 1, C designates a vertically-disposed rim at the peripheral edge of the roof that is spaced some 100 distance inwardly from the side wall of the tank, and D designates swinging hangers on said rim pivotally connected at 1 to the rim and provided with arms that project upwardly or radially over the top edge of the rim so as to serve as supports for a structure of the kind commonly referred to as a "seal", which closes the space between the rim C and the side wall A of the tank.

Said seal comprises a number of segmental shoe members E that are disposed vertically in 110

parallel or substantially parallel relation with the side wall of the tank, a substantially horizontally-disposed, annular, flexible member F, usually constructed of gas-tight fabric, attached 5 at its outer edge to the shoe members E and attached at its inner edge to the rim C of the roof, and a plurality of vertically-disposed flexible or pliable members G, usually constructed of gas-tight fabric, attached to the adjacent ends of the 10 shoe members E and to the fabric F. Instead of constructing the shoe members E from fairly heavy metal plates and mounting said shoe members directly on the hangers D, as has heretofore been the usual practice in seals of this general 15 type, I form the shoe members from relatively thin metal plates that are attached to carriers H, which, in turn, are mounted on or suspended from the hangers D, preferably by pivotal connections. The carriers H are herein illustrated as 20 consisting of vertically-disposed members formed from flat strips of metal, usually about 3 inches in width, having their upper and lower end portions flared or bent inwardly away from the side wall of the tank, and each of said carriers is 25 provided adjacent its upper end with a pair of inwardly-projecting lugs 1' that receive a bolt or pintle pin 2 which passes through a hole in the outwardly-projecting portion of one of the hangers D. The shoe members E are preferably made 30 approximately twice as long as has heretofore been the practice, and each shoe member is mounted on two carriers H, which, in turn, are suspended from two hangers D. Each carrier has a straight portion between its pivot and its 35 flared upper end, so that the outward pressure exerted on the carrier by its hanger will throw the lower end of the carrier outwardly towards the side wall of the tank.

The carriers H are arranged on the outside 40 of the shoe members so as to prevent the end portions of the shoe members from bearing upon or contacting directly with the inner face of the side wall of the tank, and the outer surface of the intermediate portion of each shoe member, 45 lying between the pair of carriers on which the shoe member is mounted, is protected by a plurality of vertically-disposed guides I formed from strips of relatively light gage metal, usually 50 metal of about $\frac{1}{8}$ of an inch in thickness, the guides I being shorter than the carriers H, and having their end portions flared or bent inwardly 55 away from the side wall of the tank so that they will co-operate with the carriers H to guide the shoe members over the side wall and prevent said shoe members from catching on rivet heads or other projections on the inner face of the side wall of the tank.

It is immaterial, so far as my broad idea is concerned, what means is employed to attach 60 the shoe members to the carriers and attach the guides I to the shoe members. In the seal herein illustrated the carriers H are provided adjacent their lower ends with fingers or brackets 3 that project inwardly from the inner faces of the carriers and serve as supports for the shoe members E, said fingers or brackets being formed either by 65 separate devices that are attached to the carriers, or formed by slitting and bending the carriers in such a way as to form integral portions on the inner sides of same that act as supports for the shoe members. Each shoe member is provided in its bottom edge with notches 4 for receiving the portions or devices 3 on the carriers that support or sustain the shoe member. 70 The upper edge portion of each shoe member E

is clamped against the inner sides of the two carriers H on which the shoe member is mounted by means of clips or clamping devices J of the kind shown in Figures 1 and 3 that are attached to the carriers by the bolts 2, previously mentioned, which pivotally connect the carriers to the hangers D, the devices J being of bar-like form and arranged so that their upper ends will bear against the inner sides of the carriers and their lower ends will lap over the top edge portion of the shoe member and exert pressure on the shoe member in a direction to hold it against the carriers and prevent it from moving inwardly relatively to the carriers. The guides I are combined with the shoe members in such a way that they are in effect simply hung upon the outer sides of the shoe members. Preferably each guide I is provided adjacent its upper end with an inwardly-projecting device 5 shaped so that it can be hooked over the top edge of the shoe member and then bent down or deformed so as to hold the guide in position. The device 5 may consist either of a separate part that is attached to the guide, or it may consist of an integral portion of the guide produced by slitting and bending the guide so as to form a portion at the inner side of the guide that can be hooked over the top edge of the shoe member. At the lower end of each guide I is an inwardly-projecting device 6 that is arranged in a slot 7 in the bottom edge of the shoe member, as shown in Figures 2 and 6, the device 6 being formed either by slitting and bending the guide, or formed by a separate part that is attached to the inner side of the guide. If desired, the bottom edge portions 105 of the shoe members may be provided with slits 7a so as to impart greater flexibility to said portions.

Instead of using rivets to attach the fabric members F and G to the parts of the structure with which they coact, I have devised a novel attaching or securing means for said fabric parts that overcomes the necessity of lining up matched holes in the fabric parts and metallic parts, and which, in addition to greatly simplifying the assembling and disassembling of the parts of the seal, produces a seal which is not liable to become leaky, due to holes in the fabric parts of the seal. Briefly stated, this feature of my invention consists in using clamps, instead of rivets, bolts or similar fastening devices to attach some or all of the fabric portions of the structure to the elements with which they coact. In the particular form of my invention shown in Figure 1, the fabric member F which joins the shoe members to the rim C on the roof, has its outer edge portion folded so as to embrace the top edges of the shoe members E. After the folded portion of the fabric has been applied to the shoe members, it is held in position by clamps, herein illustrated as consisting of substantially U-shaped clips 8 that are driven downwardly over the folded portion of the fabric, after which the side legs of said clips are pressed inwardly or towards each other so as to firmly clamp the fabric F to the top edge portions of the shoe members. The inner edge of the fabric member F is attached by similar clips 9 to an upwardly-projecting flange 10 that extends continuously around the rim C of the roof. While I prefer to fold or shape the fabric F in such a way that the edge portions of same will embrace the parts to which the fabric is attached, it is not absolutely necessary that this be done. If desired, the edge portion of the fabric can be left flat or unfolded, as shown in Figure 7, and 110

instead of using separate clips or clamps to secure the fabric, it can be secured by an integral bent portion 8^a on the part to which the fabric is attached, as shown in Figure 8. The means used 5 to join the vertically-disposed fabric members G to the adjacent ends of the shoe members E, also consists of or comprises clamps, and it has the added advantage of enabling the fabric members G to be installed or removed by workmen 10 located on the top side of the roof. While I have herein illustrated it as being used for attaching the fabric member G to the shoe members E, it is capable of use at any point or in any part of a floating tank roof seal of the general 15 type first mentioned, that requires or involves a connection between a fabric part and a metal part of the seal. Briefly stated, the holding means or attaching means just referred to consists of metallic members K permanently attached to or combined with the vertical edges of 20 each fabric member G, co-acting portions L on the adjacent ends of the shoe members, and retaining devices M that are adapted to be driven into position from the top side of the roof, so as 25 to bind or clamp the metallic parts K on the fabric member G to the co-acting parts L on the shoe members. As shown in Figure 4, the adjacent ends of the shoe members E are provided with substantially vertically-disposed trough-shaped portions L, and the fabric member G has 30 attached to its vertical edges metallic devices K that are of substantially angle shape and so proportioned that they can be slid downwardly into the trough-shaped portions L on the shoe members. 35 Non-hardening putty or a similar sealing substance is then forced downwardly into the trough-shaped portions L on the shoe members, after which rods M are driven downwardly 40 into said trough-shaped portions so as to securely bind to same the flanged devices K on the fabric member G, thereby producing gas-tight joints between the trough-shaped members L on the adjacent ends of the shoe members and the 45 flanged devices on the fabric member G that closes the gap between the ends of two adjacent shoe members. If it becomes necessary to remove the vertically-disposed fabric members G, this can be accomplished quickly and easily simply by withdrawing the retaining rods M or 50 moving them upwardly out of engagement with the parts K and L which they clamp together. The vertically-disposed fabric members G are attached at their upper ends in a gas-tight manner to the annular-shaped flexible member F, as, for example, by sewing said parts together with fine wire and filling the joint between said parts with flexible putty. The co-acting parts K and L on the vertically-disposed pieces of fabric G and 55 on the shoe members E, respectively, may be of various shapes or forms, and various means may be used to combine said parts or clamp them together. I prefer, however, to use retaining or clamping devices M that can be installed or removed from the top side of the roof, and I also prefer to permanently attach the parts K to the fabric pieces G, so that said fabric pieces are ready to be installed, simply by sliding the parts K on same into engagement with co-acting parts L on the shoe members and then installing the devices M. As shown in Figure 5, the devices M are provided at their upper ends with laterally-projecting arms 11 that can be grasped in the 60 operation of withdrawing the devices M when it becomes necessary to renew the fabric or disassemble the structure. 65 A floating roof seal of the construction above described weighs considerably less than the seals of this general design which are now in extensive commercial use; it comprises about one-half as many shoe members and fabric parts G for joining the ends of the shoe members together; it can be installed or removed quickly and easily by workmen located on the top side of the roof; it has segmental shoe members that are flexible enough to follow the curvature of the side wall of the tank and conform approximately to the vertical joints in said side wall; it has shoe members that will be maintained in close relationship with the side wall of the tank without contacting with or rubbing on the side wall, thereby permitting the shoe members to be painted or coated with a protecting substance that is not liable to be rubbed off; and it permits the use of spring assemblies, each of which comprises a single spring O for forcing the shoe members outwardly towards the side wall of the tank and maintaining said shoe members in parallel relationship with said side wall. In assembling the structure it is preferable to first install one hanger and carrier on the rim C, then position one of the shoe members E on the inner side of the carrier so that the notch 4 in the bottom edge of the shoe member will receive the inwardly-projecting supporting devices 3 on the carrier, then install the other hanger and carrier and position the shoe member on the supporting device 3 of said second carrier, then attach a vertically-disposed fabric member G to one end of the shoe member by means of the rod M provided for this purpose, which rod is driven downwardly into the trough-shaped portion L on the shoe member, then attach the horizontally-disposed fabric member F to the top edge of the shoe member 100 by a suitable clamping means, for example U-shaped retaining devices, then attach the upper end of the fabric member G to the fabric member F in such a way as to produce a gas-tight joint between said parts, then apply the guides I to 105 the outer side of the shoe member and secure said guides in position by bending or deforming the inwardly-projecting portions 5 of same, and thereafter secure the inner edge portion of the fabric member F to the rim C on the roof by a 110 suitable clamping means, such, for example, as the retaining devices 9. The remaining pairs of carriers and shoe members are installed in a similar manner. 115 It is, of course, not essential that the co-acting parts of the seal be assembled or combined in the specific manner just described, but one very desirable feature of a roof seal of the construction herein illustrated is that the parts of same can be installed progressively, around the rim 120 of the roof by two workmen located on the roof. Likewise, the parts of the seal can be quickly and 125 easily disassembled or dismounted. 130 Many of the individual features of my invention are capable of use with seals whose component parts are of different construction or arrangement than the seal herein shown. For example, the means used to attach the horizontally disposed fabric to the shoe members and to the rim may be used in a seal provided with shoe 135 members formed from relatively heavy metal plates that are not capable of flexing circumferentially. As previously stated, the means used to attach or secure the shoe members to the fabric members that close the gaps between the 140 145 150

ends of the shoe members, is capable of use at other points or places in the structure, and moreover, is applicable to floating tank roof seals in which the shoe members are of different construction and are mounted in a different way than the shoe members herein illustrated.

Having thus described my invention, what I claim as new and desire to secure by Letters Patent is:

10. 1. A seal for floating tank roofs, comprising a radially-movable supporting structure carried by the roof, shoe carriers sustained by said supporting structure, means for maintaining said carriers in approximately parallel relation with the side wall of the tank, shoe members sustained by said carriers and constructed from relatively limber metal plates, said shoe members being arranged in substantially parallel relation to the side wall of the tank, and guides on said shoe members that co-act with the carriers to properly guide the shoe members over the side wall of the tank and prevent them from rubbing on said wall.
15. 2. In a seal for floating tank roofs, the combination of carriers disposed in opposed relation with the side wall of the tank, vertically-disposed shoe members mounted on said carriers, supports on said carriers that sustain the weight of said shoe members, and means for clamping the shoe members to the carriers.
20. 3. In a seal for floating tank roofs, the combination of carriers disposed in opposed relation with the side wall of the tank, vertically-disposed shoe members sustained by said carriers and arranged between the carriers and the side-wall of the tank, supports on said carriers that sustain the weight of said shoe members, means for clamping the shoe members to the carriers, and upright guides on the outer surfaces of the shoe members arranged intermediate the carriers.
25. 4. In a seal for floating tank roofs, the combination of carriers disposed in opposed relation to the side wall of the tank, a vertically-disposed shoe member arranged on the inner side of said carriers and sustained by same, said shoe member being adapted to co-act with said side wall, devices on said carriers that co-act with the bottom edge portion of the shoe member to sustain the weight of same and prevent said member from shifting laterally relatively to the carriers, and clamps that co-act with the top edge portion of the shoe member to detachably hold said shoe member in operative position on the carriers.
30. 5. In a seal for floating tank roofs, the combination of carriers arranged in opposed relation to the side wall of the tank and provided on their inner sides with supports, a removable shoe member arranged vertically in engagement with the inner sides of said carriers and provided at its bottom edge with notches for receiving said supports, and clamps on the carriers that lap over the top edge of said shoe member and hold said shoe member in operative position on said carriers.
35. 6. In a seal for floating tank roofs, the combination of a shoe member provided at one end with a substantially trough-shaped part, a fabric element provided with a metallic part that is adapted to be slid longitudinally into the trough-shaped part of said shoe member, and a removable retaining device that is adapted to be inserted longitudinally into said trough-shaped part to bind or clamp the metallic part on said

fabric element and thus detachably secure said fabric element to the shoe member.

7. A seal for floating tank roofs, comprising a radially-movable supporting structure carried by the roof, carriers on said structure arranged in opposed relation to the side wall of the tank, removable, segmental metallic shoe members on said carriers that are relatively limber and capable of flexing intermediate their ends as and for the purpose described, and vertically disposed guides arranged in spaced relation on the outer side of said shoe members for preventing said shoe members from catching on projections on the inner face of the side wall of the tank when the roof moves vertically relatively to said side wall.

8. A seal for floating tank roofs, comprising radially-movable hangers carried by the roof, vertically-disposed carriers suspended from said hangers and arranged so as to bear upon the side wall of the tank, and removable segmental shoe members sustained by said carriers and mounted so as to be capable of being installed or removed by moving said shoe members vertically relatively to the carriers while the carriers are in operative position on the hangers.

9. A seal for floating tank roofs, comprising a radially-movable supporting structure provided with substantially bar-like carriers that are adapted to bear upon the inner face of the side wall of the tank, and limber metallic shoe members of substantially segmental shape, removably mounted on said carriers and disposed so that the carriers lie between the end portions of said shoe members and the tank side wall.

10. In a seal for floating tank roofs, a vertically-disposed, segmental shoe member disposed in parallel relation to the side wall of the tank, vertically-disposed guides removably mounted on the outer side of said shoe member and provided with portions that hook over the top edge of said member, and co-acting means on said guides and shoe member for detachably connecting said parts together.

11. In a liquid storage tank, the combination of a floating roof, an annular shoe arranged in substantially parallel relation to the side wall of the tank and adapted to bear on the inner side of same, said annular shoe having sufficient flexibility to adapt it to the curvature of said side wall and the vertical seams in same, a radially-movable structure on the roof provided with substantially vertically-disposed carriers that sustain said annular shoe, said carriers being arranged in spaced relationship between said shoe and the inner face of the tank side wall, and substantially vertically-disposed guides attached to the outer side of said shoe at points between said carriers so as to prevent the shoe from catching on projections on the tank side wall.

12. In a seal for floating tank roofs, the combination of a shoe member provided at one end with a substantially trough-shaped part, a flexible connecting element provided with a metallic part that is adapted to be slid longitudinally into the trough-shaped part of said shoe, and a removable retaining device that is adapted to be inserted longitudinally into said trough-shaped part to bind or clamp the metallic part on said connecting element to said trough-shaped part.

13. In a seal for floating tank roofs, the combination of a fabric member, a co-acting element provided with a substantially hook-shaped means that is adapted to embrace one edge portion of said fabric member, and a removable retaining

device that is adapted to be inserted longitudinally through said hook-shaped means to clamp or bind said fabric member to said element.

14. In a seal for floating tank roofs, the combination of a member provided with a substantially trough-shaped part, a fabric member provided with a metallic part that is adapted to be positioned in said trough-shaped part, and a removable retaining device that is adapted to be inserted endwise into said trough-shaped part to bind or clamp the metallic part on said fabric member to said trough-shaped part.

15. In a seal for floating tank roofs, the combination of substantially vertically-disposed shoe members arranged in opposed relation to the side wall of the tank, substantially vertically-disposed fabric elements for closing the gaps between said shoe members, said shoe members and fabric elements having co-acting portions arranged in telescopic relation and adapted to be engaged or disengaged by relative endwise movement in a direction substantially parallel to the side wall of the tank, and retaining devices for detachably connecting said fabric elements to the shoe members, mounted so as to be capable of being moved endwise into and out of engagement with the co-acting portions of said parts, when said shoe members are in approximately correct position.

16. In a seal for floating tank roofs, the combination of spaced shoe members arranged in opposed relation to the side wall of the tank, connecting elements disposed approximately parallel to the side wall of the tank for closing the gaps between said shoe members, end parts on said elements arranged so as to be engaged with co-acting end parts on said shoe members from the top side of the roof by moving said connecting elements downwardly so as to cause the end parts on same to telescopically engage the co-acting end parts on said shoe members, and removable retaining devices arranged so as to be installed or removed from the top side of the roof by moving them endwise into engagement with said co-acting end parts, for detachably joining said connecting elements to said shoe members.

17. In a seal for floating tank roofs, the combination of a radially-movable supporting structure carried by the roof, shoe carriers on said structure arranged in opposed relation to the side wall of the tank, removable shoe members on said carriers, mounted so as to be capable of being moved vertically into and out of engagement with said carriers while said carriers are mounted on said supporting structure, and connecting elements for closing the gaps between the shoe members, arranged substantially vertically in opposed relation to the tank side wall, said connecting elements being constructed so as to be capable of being moved endwise into or out of telescopic engagement with said shoe members.

18. In a seal for floating tank roofs, the combination of radially-movable hangers carried by the roof, carriers on said hangers disposed in opposed relation to the side wall of the tank, removable shoe members on said carriers mounted so as to be capable of being applied to or removed from said carriers from the top side of the roof by moving said shoe members vertically relatively to said carriers when said carriers are in operative position on said hangers, flexible connecting elements between the shoe members disposed in opposed relation to the tank side wall, and retaining devices for detachably securing said

connecting elements to said shoe members mounted so as to be capable of being installed or removed from the top side of the roof when the shoe members and carriers are in assembled relationship.

19. In a seal for floating tank roofs, the combination of two shoe members arranged in opposed relation to the side wall of the tank and disposed substantially vertically, a removable vertically-disposed connecting element for closing the gap between said shoe members, provided with end parts that are arranged parallel to and in telescopic engagement with the end portions of said shoe members, and retaining devices for clamping said connecting element to said shoe members, mounted so as to be capable of being moved endwise into or out of engagement with said parts and said portions.

20. In a seal for floating tank roofs, the combination of a fabric member, a co-acting element having a means that is adapted to receive one edge portion of said fabric member, and a removable bar-like device that is adapted to be inserted endwise into said means to bind or clamp said fabric member to the means of said element which receives the edge portion of said fabric member.

21. A seal for floating tank roofs, provided with a relatively limber metallic shoe disposed vertically with the major portion of its surface arranged in sliding engagement with the side wall of the tank, removable guides disposed on the outer side of said shoe extending vertically over the entire height or depth of the shoe and arranged in contact with the tank side wall, and bendable means for detachably interlocking said guides with said shoe.

22. In a liquid storage tank, the combination of a floating roof, a supporting structure at the peripheral edge of said roof, vertically-disposed carriers sustained by said supporting structure and arranged substantially parallel to and in opposed relation to the side wall of the tank, a substantially annular shoe supported by said carriers and formed by a plurality of independently removable, segmental shoe members, supports on the carriers on which the shoe members rest, and means for detachably interlocking said shoe members with said carriers, arranged so as to permit said shoe members to be installed or removed by moving said shoe members vertically relatively to the carriers while said carriers are in substantially operative position.

23. In a liquid storage tank, the combination of a floating roof, vertically-disposed, segmental shoe members arranged in sliding engagement with the side wall of the tank, a fabric member for closing the space between the roof and said shoe members, and means for producing tight joints between the fabric member, the roof and the shoe members, comprising clamps that embrace or surround imperforate edge portions of said fabric member and hold said fabric member in position by frictional pressure.

24. In a seal for floating tank roofs, the combination of a floating roof, shoe members that act on the tank side wall, a fabric member attached by tight joints to said roof and shoe member and provided with an imperforate edge portion that engages one of the elements to which it is attached, and clamps that embrace said imperforate edge portion and clamp the same tightly to said element by frictional pressure.

JOHN H. WIGGINS.
